CLAIM

The ornamental design for a part of a bottle, as shown and described.

DESCRIPTION

FIG. 1 is rear perspective view of a part of a bottle showing our new design;

FIG. 2 is a rear view thereof;

FIG. 3 is a top plan view thereof;

FIG. 4 is a front view thereof;

FIG. 5 is a bottom plan view thereof;

FIG. 6 is a side view thereof; and,

FIG. 7 is another side view thereof.

The broken line showing of a part of a bottle in FIGS. 1-7 is included for the purpose of illustrating only and forms no part of the claimed design. The dashed-dot-dashed lines shown on the bottle in FIGS. 1-7 represent the boundary line of the claimed design.
